(57) **CLAIM**

The ornamental design for a portable electric blower body, as shown and described.

DESCRIPTION

FIG. 1 is a front perspective view of a portable electric blower body in accordance with our new design;

FIG. 2 is a rear perspective view of the portable electric blower body in accordance with our new design;

FIG. 3 is a front elevational view of the portable electric blower body in accordance with our new design;

FIG. 4 is a rear elevational view of the portable electric blower body in accordance with our new design;

FIG. 5 is a top plan view of the portable electric blower body in accordance with our new design;

FIG. 6 is a bottom plan view of the portable electric blower body in accordance with our new design;

FIG. 7 is a right side elevational view of the portable electric blower body in accordance with our new design;

FIG. 8 is a left side elevational view of the portable electric blower body in accordance with our new design; and,

FIG. 9 is a front perspective view, similar to FIG. 1, of the portable electric blower body in accordance with our new design illustrating a state in which a nozzle is attached to the portable electric blower body.

The broken line showing of the nozzle in FIG. 9 is provided for the purpose of illustrating environmental structures; whereas the broken line showing in FIGS. 1-8, and the broken line showing in FIG. 9 other than that of the nozzle illustrate portions of the portable electric blower body. These broken line subject matters do not form part of the claimed design.
